UNITED STATES PATENT OFFICE.

CHARLES A. FISCHER, OF CHICAGO, ILLINOIS, ASSIGNOR TO ALLIS-CHALMERS COMPANY, OF MILWAUKEE, WISCONSIN, A CORPORATION OF NEW JERSEY.

FURNACE-JACKET.

1,012,831.

Specification of Letters Patent. Patented Dec. 26, 1911.

Application filed October 14, 1911. Serial No. 654,718.

To all whom it may concern:

Be it known that I, CHARLES A. FISCHER, a citizen of the United States, residing at Chicago, in the county of Cook and State 5 of Illinois, have invented a certain new and useful Improvement in Furnace-Jackets, of which the following is a specification.

This invention relates to improvements in the construction of smelting furnaces for 10 ores, and particularly to improvements in the construction of the water jackets of ore smelting furnaces.

The object of the invention is to provide a water jacket for smelting furnaces such 15 as cupolas, blast or similar furnaces, which is formed in a plurality of sections each of which is supported or retained by an independent truss. With this arrangement of jacket sections and trusses, the independent 20 jacket sections and the adjacent trusses can be removed at will without disturbing the remaining jacket sections.

Another object is to provide a truss for each of the jacket sections which is disconnected therefrom, thereby permitting the renewal of the jacket section without necessitating renewal of the retaining truss 25 thereof.

A clear conception of an embodiment of 30 the invention can be had by referring to the accompanying drawings forming a part of this specification, in which drawings like reference characters designate the same or similar parts in the various views.

35 Figure 1 is a general arrangement, partly in section, of a smelting furnace having one form of the invention embodied therein. Fig. 2 is an enlarged end view of one of the jacket sections and its retaining truss. Fig. 3 is a side view of one of the jacket 40 sections and its retaining truss.

The smelting furnace, see Fig. 1, consists 45 essentially of a smelting chamber and a foundation or base 7 upon which the elements forming the smelting chamber are supported. The smelting chamber is formed by a series of jacket sections 1, 10, placed side by side and forming an elongated rectangular chamber. Each of the 50 jacket sections which form the longer sides of the smelting chamber is provided with air passages or twyers 6. These twyers 6 are connected by suitable valve controlled pipes with the main air inlet pipe 8. The 55 main water inlet pipe 9 to the jackets is

provided with a series of branch pipes adapted to supply the cooling water to the jacket sections 1, 10, during normal operation of the furnace. The jacket sections 1, 10, are retained in a substantially vertical 60 position by means of retaining trusses, there being an individual truss for each jacket section 1. The upper ends of the jacket sections coact with the upper portion 11 of the furnace wall, the lower ends resting 65 upon the foundation or base 7. The individual jacket trusses consist essentially of a tiepiece 3 having cross-stays 2 fixed thereto at a number of points along its length. A brace 4 contacts directly with 70 the ends of the tiepiece 3 and retains this tie-piece at various points along its length through retaining or stay rods 5.

The trusses when in normal position contact with the outer sheets of the jacket sections 1, 10, along the cross-stays 2. The lower ends of the trusses are fitted into recesses formed in the base 7, while the upper ends are retained by means of clamps or jack screws 12. The trusses can be easily 80 removed by withdrawing the jack screws 12 and raising the truss bodily out of the recess 7. After removal of the truss, the jacket sections 1, 10, against which the truss normally coacts, can be readily removed. 85 On account of the relatively short width of the ends of the smelting chamber, it being customary to form these ends of only two jacket sections 10, it may be desirable to have the truss or retaining member for the 90 end jacket sections 10 common to both of them. The reason for such construction is that in removing the end jacket sections it is usually desirable to remove both sections at the same time, the construction therefore 95 being simplified by having a common truss instead of individual trusses.

It will be seen that with the construction 100 of jackets having an independent truss for retaining each of the jacket sections, any one of the sections can be easily removed without disturbing the retaining trusses of any of the other sections. It will also be seen that by having the trusses disconnected from the jacket sections, the individual 105 jacket sections can be removed and replaced by new ones if desired without replacing the corresponding jacket truss. As the jacket sections 1, 10, often become disabled and need replacing, the latter feature is a 110

very important one since it permits the continuous use of a truss until the truss is no longer fit for use.

It should be understood that it is not desired to be limited to the exact details of construction shown and described, for obvious modifications will occur to a person skilled in the art.

It is claimed and desired to secure by Letters Patent,—

1. In a furnace, a plurality of jacket sections and an independent truss for retaining each of said sections in normal position.
2. In a furnace, a plurality of jacket sections forming a smelting chamber, and an individual truss for retaining each of said jacket sections in normal position.

3. In a furnace, a plurality of jacket sections forming a smelting chamber, and a truss in contact with each of said jacket sections, said truss being independent of and disconnected from the adjacent section.

4. In a furnace, a plurality of jacket sections forming a smelting chamber, and an individual truss for retaining each of said jacket sections in normal position, at least one of said jacket sections being removable independently of the adjacent sections.

In testimony whereof, the signature of the inventor is affixed hereto in the presence of two witnesses.

CHAS. A. FISCHER.
